UNITED STATES PATENT OFFICE.

LOUIS JOSEPH HABERKORN, OF CHATSWORTH, ILLINOIS.

PUZZLE GAME.

1,223,164.

Specification of Letters Patent. Patented Apr. 17, 1917.

Application filed July 12, 1916. Serial No. 108,819.

To all whom it may concern:

Be it known that I, LOUIS JOSEPH HABERKORN, a citizen of the United States, and a resident of Chatsworth, in the county of Livingston and State of Illinois, have invented a new and Improved Puzzle Game, of which the following is a full, clear, and exact description.

This invention relates to games and toys and has particular reference to a game in the nature of a puzzle comprising a tray having a flat bottom upon which are loosely and movably supported a plurality of traps or pockets and a plurality of differently colored balls.

Among the objects of the invention is to devise a puzzle game designed to attract peculiar interest at the present time of international controversy, since one of the balls may be distinctively colored to represent an outlaw or bandit, while the remaining balls may be colored red, white, and blue, and represent an authoritative force attempting to capture the bandit by cornering him in each of the traps in succession, but the traps being removed from the tray as fast as they are filled in succession.

Another object of the invention is to provide added zest in the playing of the game by calling forth the exercise of skill of the eye, as well as the hand in manipulating the freely movable balls.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views and in which—

Figure 1 is a perspective view indicating the tray and the movable parts therein;

Fig. 2 is a vertical transverse section of the same; and

Fig. 3 is a detail perspective view of one of the many modified forms of traps that may be employed.

Referring now more particularly to the drawings, I show at 10 a tray comprising a flat bottom 11 and an upstanding vertical

rim or flange 12. This tray is shown as of circular form, but as to this I do not care to be unnecessarily limited.

Within the tray and supported loosely upon the bottom thereof are a plurality of traps 13. Being loose, these traps are adapted to slide around more or less upon the smooth flat bottom of the tray, whereby the difficulty in solving the game is increased.

A series of balls shown at 14, 15, and 16, which may be red, white, and blue, respectively, are contained within the tray and are freely rollable upon the flat bottom thereof. Also a brown ball 17 is similarly located.

While in the preferred form the traps are shown as of open angular form, they may also be of different forms, but adapted to be self supporting with an open side into which the balls may be caused to roll and be held by the sides of the trap. Fig. 3 indicates a semi-circular trap 13^a as a substantial equivalent of the triangular form. 75

With the parts designed as shown or suggested herein and all of the parts arranged within the tray, the game may be proceeded with substantially as follows: Considering, for example, the brown ball 17 as the bandit to be captured by the red, white, and blue, the object will be to roll the brown ball into the angle of one of the traps and then roll the other three balls so that they will inclose the brown ball in such position. The operator then removes the trap thus filled from the board and proceeds with another trap and so on throughout the entire series of traps. When the bandit is finally captured in the last of the series of traps, the game is 90 won.

I am aware that it is not new broadly to provide a tray with pockets or traps of different characters with rolling devices to be caused to enter such pockets or traps, but so far as I am aware, I believe it is new with me to employ a series of freely slidable or movable traps of the character and nature indicated herein.

I claim:

1. The combination with a tray having a smooth bottom and an upstanding rim surrounding the same, of a plurality of erect open sided traps loosely and movably supported upon the bottom within the tray, 105 and a series of differently colored rolling

100

105

members likewise contained within the tray and adapted to be caused to enter each of the traps in succession.

2. The combination with a tray having a smooth flat bottom and a circular rim surrounding the same and projecting upwardly above the bottom, of a series of self support-

ing traps slidably supported upon the smooth flat bottom and each having an open side, and a series of differently colored balls 10 adapted to be caused to be rolled into each of the traps in succession in a certain predetermined order.

LOUIS JOSEPH HABERKORN.
